J. C. HOLCOM.
BELLOWS FOR PNEUMATIC LEAF TURNERS.
APPLICATION FILED JAN. 26, 1916.

Patented Feb. 20, 1917.

1,216,693.

THE NORRIS PETERS CO., PHOTO-LITHO., WASHINGTON, D. C.

UNITED STATES PATENT OFFICE.

JARRET C. HOLCOM, OF SULPHUR SPRINGS, TEXAS.

BELLOWS FOR PNEUMATIC LEAF-TURNERS.

1,216,693.

Specification of Letters Patent.

Patented Feb. 20, 1917.

Original application filed September 22, 1915, Serial No. 51,916. Divided and this application filed January 26, 1916. Serial No. 74,382.

To all whom it may concern:

Be it known that I, JARRET C. HOLCOM, a citizen of the United States, residing at Sulphur Springs, in the county of Hopkins and State of Texas, have invented certain new and useful Improvements in Bellows for Pneumatic Leaf-Turners, of which the following is a specification.

This invention relates to bellows for operating leaf-turners and consists in certain novel features hereinafter described and claimed, the present application being a division of an application filed by me September 22, 1915, Serial No. 51,916.

15 The invention is illustrated in the accompanying drawings in which—

Figure 1 is a detail perspective view of the bellows;

20 Fig. 2 is a vertical section of the same; Fig. 3 is a detail perspective view of a portion of the mechanism.

The invention relates particularly to the primary actuating members of apparatus for pneumatically turning the leaves or 25 sheets of a musical composition.

In applying the apparatus to a piano, I secure to the back or inner side of the piano desk, a housing in which the mechanism acting directly upon the sheets of music is contained. I also mount in the piano case, near the usual pedals, a pair of pedals 4 which are intended to be actuated by the performer to operate the leaf-turning arms. A housing 5 is secured to the inner side of the piano casing and this housing contains a pair of bellows 6 from which flexible conductors or pipes 7 extend to the top of the upper first-mentioned housing. The pedals 4 are fulcrumed between lugs or ears 9 secured to the 30 forward wall of the respective bellows 6 and the pedals project forwardly through openings in the piano case below the panel 10, wear plates 11 being provided around said openings to impart a neat finish thereto.

45 Between the upturned portions 12 of the pedals and the panel 10, I provide coiled springs 13 each having one terminal 14 bearing against the upturned portion of the adjacent pedal and its other terminal 15 fitted in a sleeve or keeper 16 which is secured to the panel 10, as clearly shown in Fig. 4. The coils of these springs are disposed below brackets 17 secured upon the forward walls of the bellows and containing coiled springs 50 18 which bear upon the extremities of the

upturned portions 12 of the respective pedals. Each hose or tube 7 has its lower end fitted to an inlet tube 20 in the rear wall of the bellows and, in the front wall of the bellows, I provide an outlet opening 21 which is normally covered by a valve 22 pivotally secured upon the wall of the bellows and held normally in a closed position by a spring 23 secured to the bellows wall and bearing upon the valve, as shown clearly in Fig. 1. It will be readily understood that these valves open away from the bellows and when either pedal 4 is depressed, the pressure exerted through the upturned branch thereof upon the bracket 17 against the tension of the spring 18, will swing the forward wall of the bellows toward the panel 10, thereby expanding the bellows and creating a suction through the hose or tube 7. When the pedal is released, the springs 13 and 18 at once expand and return the parts to the initial or normal position so that the bellows will be closed, the air then in the bellows overcoming the force of the spring 23 so that the valve 22 will be opened and the air will escape. The air finds its way from the housing 5 through the opening around the pedal, as will be readily understood.

The upper end of each tube 7 is operatively connected with a pneumatic motor (not shown) within the housing carried by the piano desk or music stand. These motors are disposed at opposite sides of a series of leaf-turning arms and act on said arms through intermediate devices so that one motor will swing the arms in one direction and the other motor will swing the arms in the other direction. The leaf-turning arms are provided with jaws which clamp the several leaves so that each arm carries one leaf.

The performer depresses the right pedal 4 at the conclusion of each page of the composition and thereby successively swings the leaf carrying arms from the right side of the music stand to the left side thereof. After the performance is finished, the left pedal will be depressed so as to carry the leaves or sheets successively back to the initial position. When the pedal 4 is depressed, the bellows connected therewith will be expanded so as to create a suction through the pneumatic motor which is in communication therewith and, consequently, the movable side of the motor will be swung toward the 110

fixed side thereof and a pull exerted upon the foremost leaf-turning arm so as to swing the same out from the music stand or the piano desk and then around to the left.

5 When it is desired to return the sheets to their initial position, the left pedal is manipulated to actuate the motor connected therewith and thereby swing the leaf-turning arms successively to the right.

10 Having thus described the invention, what is claimed as new is:

1. In an apparatus for the purpose set forth, the combination of a bellows, a support for the same, a pedal pivoted upon the bellows and connected therewith to actuate the same, and means acting on the pedal to yieldably hold the bellows in a collapsed condition.

2. In a leaf turning apparatus, the com-

20 nation of a support, a bellows mounted therein, a pedal, yieldable connections between the pedal and the bellows, and means on the support and bearing on the pedal to yieldably hold the bellows in a collapsed condition.

25 3. The combination of a support, a bellows mounted therein, a pedal mounted within the support and projecting through the same and provided with an upstanding arm bearing upon the bellows, a bracket secured upon the bellows, a coil spring fitted within said bracket and bearing upon the upstanding portion of the pedal, and a spring secured to the support and bearing upon said bracket.

30 35 In testimony whereof I affix my signature.

JARRET C. HOLCOM. [L.S.]
